(57) **CLAIM**

The ornamental design for a suture anchor device, as shown and described.

DESCRIPTION

FIG. 1 is a perspective view of a new design for a suture anchor device;

FIG. 2 is a second perspective view thereof;

FIG. 3 is a front side view thereof, the rear side view thereof being identical in appearance;

FIG. 4 is a right side view thereof, the left side view thereof being identical in appearance;

FIG. 5 is an enlarged top view thereof; and,

FIG. 6 is an enlarged bottom view thereof.

The broken lines immediately adjacent to the shaded areas represent the bounds of the claimed design while all other broken lines represent environmental structure and are for illustrative purposes only; the broken lines form no part of the claimed design.

1 Claim, 4 Drawing Sheets

FIG. 1

FIG.2

FIG. 5

FIG. 6

UNITED STATES PATENT AND TRADEMARK OFFICE
CERTIFICATE OF CORRECTION

PATENT NO. : D649,248 S
APPLICATION NO. : 29/376038
DATED : November 22, 2011
INVENTOR(S) : Griffis, III et al.

Page 1 of 1

It is certified that error appears in the above-identified patent and that said Letters Patent is hereby corrected as shown below:

In the Title page Item (12) & Item (75), the Inventors, line 1, replace “Griffs” with --Griffis--;

In the last line of the Description, replace “clamed” with --claimed--.

Signed and Sealed this
Seventh Day of February, 2012

David J. Kappos
Director of the United States Patent and Trademark Office
